METALLIC CONTAINER

Wallace C. Mills, Rockford, Ill., assignor to J. L. Clark Manufacturing Co., Rockford, Ill., a corporation of Illinois

Application November 4, 1936, Serial No. 109,067

2 Claims. (Cl. 220—10)

The invention relates to small jars of the type employed as containers for cold cream, ointments, and the like. It has heretofore been proposed to construct such containers of cooperating inner and outer sheet metal shells, as, for example, in the manner shown in Patent No. 2,044,093, issued June 16, 1936, in order to reduce the weight and fragility of the article as compared to a similar container made of glass, and also to obtain other advantages resulting from the use of a metal container.

One object of the present invention is to provide an improved container of the type set forth having a screw-threaded cap or closure, the construction being of such character that there is no danger of moving the inner and outer shells relative to each other while screwing the cap on or off even though the shells are held together by a simple frictional joint.

20 The invention also resides in certain structural improvements in the device whereby the fabrication of the parts and their assembly are simplified.

Further objects and advantages of the invention will become apparent as the following description proceeds and the features of novelty which characterize the invention are pointed out with particularity in the claims annexed to and forming a part of this specification.

30 For a better understanding of the invention, reference may be had to the accompanying drawing in which:

Figure 1 is a perspective view of a sheet metal container embodying the invention.

35 Fig. 2 is an enlarged side elevation, partly in section, of the container shown in Fig. 1.

Fig. 3 is a fragmentary sectional detail view illustrating particularly a modified form of joint between the inner and outer shells of a container such as that shown in Fig. 1.

40 For purposes of illustration, the invention has been shown as embodied in a jar or container particularly adapted for cold cream or similar viscous cosmetics and the like. This container is of a double walled construction made up of inner and outer sheet metal shells which are preferably secured together by a simple frictional joint. The shells are so fashioned that the interior of the container will have an entirely smooth surface terminating in a broad rounded edge at the top of the container while the outer shell is fashioned for threaded engagement with a closure cap which is out of contact with the inner shell, thus preventing dislodgment of the frictional inter-shell joint when screwing the

cap on or off. The particular container illustrated comprises inner and outer shells designated generally by the numerals 10 and 11, respectively, and a cooperating closure cap 12.

To provide an interior surface entirely free from joints or crevices, the inner shell 10 is preferably cup-shaped and formed from a single sheet of metal drawn to provide a bottom wall 13 and a side wall 14 terminating in a comparatively wide outwardly flaring lip 15 extending entirely about the upper edge of the inner shell. The lip 15 thus forms a smooth continuation of the inner side walls of the container so that there is no crevice nor irregularity in which the contents of the jar may become lodged, especially while removing the same. In the preferred construction illustrated, the lip 15 also includes a downwardly projecting portion 16 disposed in spaced relation with respect to the adjacent upper end of the side wall of the shell and cooperating with the adjacent edge of the outer shell 11 to hold the same in assembled relation as is hereinafter described in greater detail.

The upper end portion of the outer shell 11 is inset as indicated at 17 in order to form a neck 25 of reduced diameter on which the cap 12 is telescoped so that the exterior surface of the sides of the cap form a smooth continuation of the exterior side walls of the outer shell 11. It will be noted that the neck 17 terminates in an annular upwardly facing shoulder 18 on which the lower edge of the cap rests. A second and smaller shoulder 19 is preferably formed in the outer shell 11 and the edge of the inner shell rests against this shoulder. In assembling the 30 inner and outer shells, the upper edge of the outer shell 11 is preferably press fitted within the downwardly extending portion 16 of the inner shell 10 so as to frictionally retain the shells in assembled relation.

40 The cap 12 includes in general a horizontal top wall and a depending annular skirt portion. In the container illustrated the cap is also of double walled construction and includes inner and outer cup-shaped sheet metal shells 20 and 21, 45 respectively. The top wall of the outer shell 21 is dished upwardly to give the top of the cap a pleasing rounded contour. Upon reference to Fig. 2, it will be seen that the lower edges 22 of the outer cap shell 21 are folded inwardly over the adjacent edges of the inner cap shell 20 to form a smooth lower edge for the cap and at the same time, retain the shells in assembled relation with a firm clamping action.

50 The cap 12 is detachably maintained in posi-

tion by means forming a screw threaded engagement with the outer shell, preferably in the form of interfitting projections on these parts. Thus, in the preferred construction illustrated, generally helical ridges or threads 23 are formed in the outer body shell 11 and cooperate with complementary inwardly extending ridges or threads 24 formed in the inner cap shell 20. It will thus be seen that even if the cap 12 becomes stuck 10 and the user exerts a strong torsional force in attempting to unscrew it, there will be no danger of twisting the inner and outer shells with respect to each other as would be the case if the cap were threaded on the inner shell, for example. At the same time, the advantages of the smooth interior wall construction which is so highly desirable in a container of this type are retained.

The lower end of the inner shell 10 is carried 20 by a supporting disk 25 loosely mounted within the outer shell 11. Thus, this disk rests on the inwardly and upwardly curled portion 26 of the outer shell 11. A recess formed in the center of the supporting disk 25 serves to center the same 25 upon insertion of the inner shell 10. The disk illustrated is provided with an annular upstanding central portion 27, which is dished downwardly as indicated at 28. In the assembly of the container, the disk 25 is first dropped into 30 the outer shell 11 and rests loosely on the projection 26. The inner shell 10 is then inserted into the outer shell and as its lower end wall 13 is received by the recess 28, the disk 25 is properly centered. During the completion of the 35 insertion of the inner shell 10, its edge portion 16 is press fitted over the upper edge of the outer shell 11. It will thus be seen that the assembly operation is very simple and that the component parts are also of simple construction with maximum tolerances in their dimensions.

Fig. 3 illustrates a modified form of frictional connection which may be utilized between the inner and outer shells of a container of the general type described above. This container 45 includes inner and outer shells 10^a and 11^a which may be identical in construction with the shells 10 and 11 described above except for the interlocking edge portions thereof. Thus, the upper end of the cup-shaped inner sheet metal shell 50 10^a terminates in an outwardly flaring smooth lip 15^a of substantial width which forms a smooth continuation of the inner side walls of the shell. The edge of the lip 15^a is bent inwardly and interlocked with the adjacent upper edge of the 55 outer shell 11^a to form a double seam as indicated at 29. An inset neck portion 17^a is formed at the top of the outer shell 11^a on which a suitable cap such as the cap 12 described above may be telescoped. This neck portion terminates in an upwardly facing shoulder 18^a which

abuts the lower edge of the cap skirt. Threaded engagement between the cap and outer shell 11^a is had by complementary threads identical with those described above, one of the thread indentations 23^a on the outer shell 11^a being indicated in Fig. 3. In assembling a container having a joint such as that shown in Fig. 3, it is desirable to form the seam 29 before the lower end of the space between the inner and outer body shells is closed so that an anvil can be inserted therebetween for use in forming the joint. In such case, it is desirable to make the bottom supporting disk of flexible material or of such shape that it may be inserted after the insertion of the inner shell 10^a.

Although certain preferred embodiments of the invention have been shown and described in some detail for purposes of illustration, there is no intention to thereby limit the invention to such embodiments but, on the other hand, the appended claims are intended to cover all modifications within the spirit and scope of the invention.

I claim as my invention:

1. A container of the class set forth comprising a tubular outer shell having an inwardly extending projection formed about at least a portion of the lower end thereof, a supporting disk loosely mounted within said outer shell on said projection, a cup-shaped inner shell inserted into said outer shell in the assembly of the container, said disk being provided with a centrally located recess therein embracing the lower end of said inner shell, whereby said loosely mounted disk is centered by the lower end of said inner shell upon the insertion thereof, and means securing the upper portions of said shells together in assembled relation.

2. A container of the class set forth comprising a cup-shaped inner shell and an outer shell disposed in spaced relation, the outer shell having its upper end portion offset inwardly to form an annular shoulder spaced below the upper end of the outer shell and providing an integral threaded neck portion on the outer shell, said neck portion being spaced outwardly from the upper end of the inner shell and said inner shell having an outwardly flaring lip at its upper end overlapping the upper end of the neck portion of the outer shell and closing the upper end of the space between the two shells, the overlapping portion of the lip extending down about the neck in substantially flush relation with the threaded portion of the latter and constituting an extension thereof, and a cover having a skirt fitting over the neck portion of the outer shell and having a screw threaded connection with the outer shell through the integral neck portion thereof.

WALLACE C. MILLS.
